UNITED STATES PATENT OFFICE.

MARGUERITE LÉONE CASIMIER, OF CHICAGO, ILLINOIS.

DESIGN FOR A FLAG.

52,946.

Specification for Design.

Patented Feb. 4, 1919.

Application filed October 24, 1918. Serial No. 259,591. Term of patent 14 years.

To all whom it may concern:

Be it known that I, MARGUERITE LÉONE CASIMIER, a citizen of the United States, residing at Chicago, in the county of Cook and State of Illinois, have invented a new, original, and ornamental Design for a Flag, of which the following is a specification, reference being had to the accompanying drawing, forming a part thereof.

The single figure of drawing shows a front view of a flag, illustrating my new design.

I claim:—

The ornamental design for a flag as shown.

MARGUERITE LÉONE CASIMIER.
